UNITED STATES PATENT OFFICE.

WILLIAM HENRY SMITH, OF PENGE, LONDON, ENGLAND, ASSIGNOR TO JOSEPH HERBERT MARSHALL, OF LONDON, ENGLAND.

ELECTRIC PIANO-PLAYER.

979,715.

Specification of Letters Patent.

Patented Dec. 27, 1910.

Application filed February 23, 1909. Serial No. 479,421.

To all whom it may concern:

Be it known that I, WILLIAM HENRY SMITH, a subject of the King of England, residing at Penge, London, England, have 5 invented certain new and useful Improvements in Electric Piano-Players, of which the following is a specification.

This invention relates to improvements in automatic musical instruments, that is 10 to say, to piano-players and the like which are actuated partly or entirely by electrical means. The operation of the striking mechanism is effected by electrical means, but the music sheet may control the apparatus either 15 pneumatically or electrically.

The invention will be described with reference to the accompanying drawings, in which—

Figure 1 is a diagrammatic view of the 20 connections and apparatus employed, according to one method for carrying out the invention. Fig. 2 is a diagrammatic view illustrating the circuit connections by which a single actuating device may control a 25 group of notes. Fig. 3 is a view of the modification of the cut-out arm adapted to control a group of notes. Fig. 4 is a fragmentary view of the tracker-board showing the 30 pneumatic connections of the same with the several electric contacts.

An electro-magnet A has coöperating with it a pivoted armature A¹ and connected to the armature is a striker B for operation on the keys of the piano; one key is indicated at C. The armature is connected to the striker by a screw-threaded eye A² that pivoted to a lug B¹ carried by the striker and by screwing the eye farther into or out from the armature the length of stroke given 40 to the striker may be adjusted. Normally the armature is retained in the position shown in the drawing by a spring B² surrounding the striker coöperating with a fixed frame member X and a stop B³ also coöperating with the same frame member limits the upward movement of the striker. The 45 position in which the armature is shown is that wherein the magnetic field acts most strongly upon it. It will be seen that each end of the armature is approaching one of the poles of the electro-magnet and when the electro-magnet is excited the armature moves in the direction of the arrow so as to take up a position in line with the poles. 50 It follows therefore that it moves from the

position where the greatest torque is exercised to one where the magnetic field acts less strongly upon it and when absolutely in line with the poles the torque is *nil*. The advantage of this arrangement is that the strongest force is exercised when movement of the striking mechanism is commenced and after this the force exerted is decreased.

There are as many strikers employed as keys C that are to be operated but as these are all alike it is not necessary to show more than one. One end of the coil of the electro-magnet A for each striker is connected by wire D through a contact device E to a battery F. The other end of the coil is connected through a non-inductive high resistance G and a wire D¹ to the other pole of the battery F. This end of the coil however also has another connection with the same pole of the battery by way of a "cut-out" H. This "cut-out" serves to shunt the resistance G and comprises a contact piece H¹ that is carried by a rocking arm N and a coöperating contact-piece H² that is mounted in an arm H³ pivoted at H⁴ to the 75 rocking arm N and controlled by a spring H⁵. The position of the rocking arm N may be regulated by any suitable means that can be operated while the instrument is in use. A screw N¹ is shown for this purpose. 80 This means of adjustment is not merely for the purpose of facilitating the assembling of the instrument in the factory but is intended to accomplish a definite result with respect to the operation of the instrument. By adjusting the connection between the cut-out and the striker, the full current will be maintained for a longer or shorter period and thus the notes struck will be correspondingly stronger or weaker.

The circuit 90 through the "cut-out" H is by way of a wire J, a switch J¹, a rheostat J² of low resistance and a wire J³. With the switch J¹ in the position shown in the drawing and when the special accenting device L, herein-after to be described, is not operated from the note sheet there is no circuit through the cut-out so that all the current for exciting the electro-magnet A must pass through the high resistance G. This is for soft playing. 95 Only and in such case the current is not diminished after the operation of the striking mechanism and during the period in which the striking mechanism is held in the operative position. For louder playing, 100

105

110

however, the switch is moved on to one or other of the contacts of the rheostat J^2 which brings the "cut-out" H into operation. It follows therefore that when the 5 circuit of the electro-magnet is first closed a comparatively large current passes through the electro-magnet as the high resistance G is cut-out by the contacts H^1 H^2 and the resistance of the rheostat is less than the resistance G or constitutes a comparatively 10 low resistance. The striker B is therefore more forcibly operated, but as soon as the note has been struck it is unnecessary to maintain this comparatively large flow of 15 current, and for this purpose the movement of the striking mechanism is made to decrease the flow of current. This is effected by a tappet B^1 that is adjustably mounted on the striker B and opposed to the arm H^3 . 20 As the striker descends, the tappet displaces the arm H^3 which carries the contact-piece H^2 and thus throws the "cut-out" H out of action; the current now has to pass through the high resistance G to the electro-magnet, and it is therefore decreased. The 25 current could otherwise be decreased in a well-known manner by reducing the number of battery cells in circuit with the electro-magnet by means of the cut-out.

20 The object of the rocking arm N is to provide for loud and soft playing. It will be seen that by rotating the screw N^1 to bring the free end of arm H^2 farther from or nearer to the tappet B^1 the full current will 30 be maintained for a longer or shorter period and thus the note or notes struck while the arm is in such position will be correspondingly stronger or weaker. The rocking arm N could carry the contact pieces of all the notes, 35 or more than one rocking arm could be provided, each carrying the contacts corresponding to a selected group of notes, thus in Fig. 3 the rocking arm N is provided with the branch arms n^1 — n^1 , etc., carrying the contact pieces H^1 — H^{1a} , etc., and the arms H^2 — H^{2a} , etc., carrying contact pieces corresponding to the contact pieces H^2 , Fig. 1. The arms H^3 — H^{3a} , etc., are arranged for engagement by the tappets B^4 — B^{4a} , etc.

50 The electro-magnets and consequently the keys C that are to be struck are conveniently controlled by the usual perforated paper roll co-operating with pneumatic apparatus, the pneumatic apparatus however 55 being employed to make electrical contacts for closing the circuits of the various electro-magnets. One of these contacts is shown at E and comprises two contact pieces E^1 E^2 that are secured within a chamber K . This 60 chamber forms part of the usual pneumatic apparatus and has a bleed hole K^1 that is connected with the vacuum chamber and a conduit K^2 that communicates with the tracker-board A^x . A diaphragm K^3 is 65 opposed to the conduit K^2 and carries a block K^4 . The block lies opposite the contact E^1 and so long as a vacuum is maintained in the chamber K it does not displace the contact. A fine passage K^5 communicates between the conduit K^2 and the chamber K so 70 that normally the diaphragm K^3 is not under pressure. As soon, however, as the opening in the tracker-board that corresponds to the conduit K^2 is uncovered by the music-sheet so that air is admitted to the 75 conduit, the pressure of the air thus suddenly admitted advances the diaphragm K^3 and causes this to bring the contact-piece E^1 into electrical contact with the piece E^2 .

80 A plurality of rheostats J^2 is provided one being in series with each electro-magnet but the switch J^1 may have several arms whereby the one switch may be made to control a group of rheostats for the purpose of accenting a corresponding group of 85 notes. Several switches may be provided each controlling its own group whereby the treble and the bass, for instance, may be separately accented. Thus in Fig. 2, the switch arm J^1 is shown as provided with a 90 plurality of arms J^{1a} — J^{1b} , to which the wires J^a — J^b are suitably connected. The arms J^{1a} — J^{1b} co-operate with the rheostats J^{2a} — J^{2b} , to which the wires J^{2a} — J^{2b} are connected. It will be seen that these rheostats 95 provide an alternative means for obtaining loud and soft playing. It has before been proposed to employ a single rheostat in series with a group of electro-magnets that control note-producing devices, but by the 100 above arrangement a much more flexible control of the note-producing mechanism is obtained, and moreover it lends itself for the purpose of accenting individual notes by means of a co-operating cut-out as follows: In some cases the music sheet is provided with special perforations for the purpose of accenting individual notes, and for dealing with these special perforations another set of contacts as L is employed. 105 These are arranged in a similar manner to the contacts E and are controlled pneumatically through conduits L^x from the tracker-board A^x by a diaphragm L^1 . Each contact L is placed in shunt to the rheostat J^2 corresponding to the note that is controlled by the particular orifice in the tracker-board whereby the accenting of such note is determined, and it follows therefore that when any such orifice is uncovered, the corresponding rheostat with its connections is cut out. The current must then pass through the wire D , the coil of the electro-magnet A , wire J , wire L^2 , contact-devices L , and 115 thence by a wire L^3 to the wire J^2 that is connected to the "cut-out" H ; a circuit is thus provided through the "cut-out" H whether the switch J^1 is in operation or not, and the wire D^1 completes the circuit to the 120 battery. An adjustable resistance L^4 may 125

be placed in circuit with the contacts L so that the degree of accenting may be controlled. Instead of a set of contacts L, one or two only may be provided. In such case, 5 each pair of contacts would operate to "cut-out" a group of rheostats so that any notes controlled by such group would be accented. Thus the treble notes could be controlled by one pair of contacts and the bass by another. 10 An arrangement of the circuits for this purpose is illustrated diagrammatically in Fig. 2, in which the connections L^2 of the accenting pneumatic L are provided with suitable connections, with the wires J^a — J^b corresponding to the wire J in Fig. 1, and the connection L^3 is branched to the wires J^{3a} — J^{3b} corresponding to the wire J^3 in 15 Fig. 1.

To prevent sparking at the contacts E, a non-inductive resistance M is conveniently placed across the coil of the electro-magnet A, but this is only a safeguard, as in normal operation, before the contacts E are separated, the contacts H' H² of the cut-out H have been separated, so that the current passing through the coil of the electro-magnet A has been reduced and very little sparking is possible. It should be noted that the non-inductive resistance G that thus serves to reduce the current and prevent sparking at E also prevents sparking at H as it is always in circuit across the contacts H' H².

Any of the devices known for automatically accenting particular notes may be arranged to control the contacts L for the purpose of effecting the accenting in the case of the present invention, and such accenting may obviously be effected by throwing in more batteries if desired, instead of cutting out a resistance such as the rheostats J². If desired, the method of accenting by extra holes controlling certain groups of notes, as described in U. S. application Smith and Gunton, No. 466,223, filed December 7, 1908, may be used in conjunction with the electrical devices above described.

This invention has been described in its application to an outside piano-player. It is to be understood that it could similarly be applied to an inside piano-player.

What I claim as my invention and desire to secure by Letters Patent is:—

1. In combination with a musical instrument, an automatic operator comprising an electromagnet, a striker operated thereby, a high resistance in series with the electromagnet, a low resistance in parallel with the high resistance, a cut-out in the low resistance circuit, and adjustable means constructed and arranged to be operated while the instrument is in use in playing a piece, operatively connecting said cut-out with said striker whereby the time of operation of said cut-out with respect to the operation of said striker may be varied.

2. In an automatic operator for a musical instrument, the combination of a plurality of electro-magnets, strikers operated thereby, a high resistance in series with each electro-magnet, a low resistance in parallel with each high resistance, a cut-out in each low resistance circuit, means for varying the resistance of the low resistance circuits, and means for operatively connecting each of said cut-outs with its corresponding striker whereby said cut-outs may be operated during the operation of said strikers. 70 75

3. In an automatic operator for a musical instrument the combination of, an electro-magnet, a striker operated thereby, a high resistance in series with the electro-magnet, a low resistance in parallel with the high resistance, a cut-out in the low resistance circuit, a pneumatically operated contact in shunt with the low resistance, and means for operatively connecting the cut-out with the striker whereby the cut-out is operated at approximately the end of the stroke, substantially as set forth. 85

4. In an automatic operator for a musical instrument the combination of an electro-magnet, a striker operated thereby, a high resistance in series with the electro-magnet, a variable low resistance in parallel with the high resistance, a cut-out in the low resistance circuit, a pneumatically operated contact in shunt with the low resistance, and means for operatively connecting the cut-out with the striker whereby the cut-out is operated at approximately the end of the stroke, substantially as set forth. 90

145

95

100

5. In an automatic operator for a musical instrument the combination of a source of electrical energy, an electro-magnet, a pneumatically-operated contact in the circuit of said electro-magnet, an armature normally in position of maximum torque, a striker operated by the armature, a lug mounted adjustably on the striker, a cut-out operated by the lug, a high resistance in series with the electro-magnet, an adjustable low resistance rheostat in parallel with the high resistance and in circuit with the cut-out, a pneumatically operated contact in parallel with the low resistance.

6. In combination with a musical instrument, an automatic operator comprising an electro-magnet, a contact in the circuit thereof, a non-inductive resistance in series with the coil of said electromagnet, a cut-out in shunt with said resistance, said resistance being arranged to prevent sparking at said contact and said cut-out respectively, a striker operated by said electromagnet, and adjustable connections between said striker and cut-out, constructed and arranged to be operated while the instrument is in use in playing a piece to vary the time of operation of said cut-out with respect to the operation of said striker. 125

7. In an automatic operator for a musical instrument, the combination of a plurality of electric circuits, a pneumatically-operated electric contact in each circuit, a perforated sheet for controlling the pneumatic apparatus, a plurality of electro-magnets, each controlled by one of said contacts, a plurality of note-actuating mechanisms each one of which is operatively connected to one of said electro-magnets, one or more other pneumatically-operated contacts, means whereby said other contacts may be governed by the perforated sheet, one or more rheostats connected in parallel with said other contacts, means whereby said other contacts may coöperate with said first mentioned contacts to accentuate any particular note or notes.

8. In an automatic operator for a musical instrument, the combination of a plurality of electro-magnets, a plurality of strikers, each striker being operated by an electro-magnet, a plurality of rheostats, one connected in series with each electro-magnet, and a plurality of operating handles each arranged to control a plurality of said rheostats, a plurality of cut-outs, one in series with each electro-magnet and operatively connected with each striker, and means for varying the time of operation of said cut-outs.

9. In an automatic operator for a musical instrument, the combination of a plurality of electro-magnets, a plurality of strikers each striker being operatively connected with one of said electro-magnets, a plurality of rheostats, one connected in series with each electro-magnet, a plurality of operating handles, each arranged to control a plurality of rheostats and an electrical contact in shunt with one or more of said rheostats, and means for operating said contact to shunt said rheostats.

10. In an automatic operator for a musical instrument, the combination of a plurality of electro-magnets, a plurality of strikers one operated by each of said magnets, a high resistance in series with each of said magnets, a low resistance in parallel with each of said high resistances, a cut-out in circuit with each of said low resistances, adjustable means operatively connecting said cut-outs with said strikers, and means whereby the

times of operation of a plurality of said cut-outs may be varied at will. 55

11. In an automatic operator for a musical instrument, the combination of a plurality of electro-magnets, a plurality of strikers each operated by one of said magnets, a high resistance in series with each of said magnets, a low resistance in parallel with each of said high resistances, cut-outs in circuit with each of said low resistances, means on said strikers coöperating with said cut-outs to control the time of operation thereof, said means being adjustable to vary the time of operation of a plurality of said cut-outs with respect to the operation of their co-operating strikers. 60 65

12. In an automatic operator for a musical instrument, the combination of a plurality of electro-magnets, strikers operated thereby, a high resistance in series with each electro-magnet, a low resistance in parallel with each high resistance, a cut-out in circuit with each low resistance, means for simultaneously varying the resistance of a plurality of said low resistances, and means operatively connecting said cut-outs with said strikers whereby said cut-outs may be operated during the operation of said strikers respectively. 70 75 80

13. In an automatic operator for a musical instrument, the combination of a plurality of electro-magnets, strikers operated thereby, a high resistance in series with each electro-magnet, a low resistance in parallel with each of said high resistances, a cut-out in circuit with each low resistance, a pneumatically operated contact in shunt with each of said low resistances, and means for simultaneously operating a plurality of said contacts to simultaneously shunt a plurality of said low resistances, and means for operatively connecting said cut-outs with said strikers whereby said cut-outs may be operated at approximately the end of the strokes of said strikers respectively. 85 90 95
